FIG. 1

FIG. 2

FIG. 3

FIG. 4

FIG. 5

FIG. 6

FIG. 7

FIGURE 1 is a side elevational view of a manifold gas valve embodying our new design;

FIGURE 2 is an end elevational view thereof taken from the right of FIGURE 1;

FIGURE 3 is a top plan view thereof;

FIGURE 4 is an end elevational view taken from the left of FIGURE 1;

FIGURE 5 is a top plan view of a modified form of the manifold gas valve, which is the same in appearance as the form shown in FIGURES 1 to 4 inclusive, except for the shallow plate member which replaces the member shown at the top right in FIGURE 1;

FIGURE 6 is a fragmentary side elevational view of the modified form; and

FIGURE 7 is a perspective view of the valve shown in FIGURE 1.

The side not shown is substantially the same in appearance as that shown in FIGURE 1.

The dominant features of the design reside in the portions shown in full lines.

We claim:

The ornamental design for a manifold gas valve or the like, substantially as shown and described.
